UNITED STATES PATENT OFFICE.

CHARLES L. BRALEY, OF CINCINNATI, OHIO, ASSIGNOR TO THE AMERICAN LAUNDRY MACHINERY COMPANY, OF CINCINNATI, OHIO, A CORPORATION OF OHIO.

TANDEM ATTACHMENT FOR IRONING-PRESSES.

1,398,834.

Specification of Letters Patent. Patented Nov. 29, 1921.

Application filed August 24, 1916. Serial No. 116,696.

To all whom it may concern:

Be it known that I, CHARLES L. BRALEY, a citizen of the United States, residing at Cincinnati, in the county of Hamilton and State 5 of Ohio, have invented certain new and useful Improvements in Tandem Attachments for Ironing-Presses, of which the following is a specification.

This invention relates to pressing machines, and more particularly to pressing machines operated in pairs by a single operator.

In the operation of a pressing machine, such as a machine for pressing garments or 15 articles of any kind, it is essential, after application of pressure to the article being pressed to hold said article under pressure for an appreciable length of time, in order to secure the best pressing results. To avoid 20 idleness of the operator while the article is being held under pressure it is customary to have a single operator manipulate two machines located adjacent each other. While 25 an article is being held under pressure in one machine, the operator places an article in the second machine and applies the pressure thereto and then goes back to the first machine, releases the pressure upon the article in said machine and feeds another article 30 thereto, and so on.

The object of the present invention is to provide improved mechanism or devices enabling the two pressing machines to be operated conjointly with a minimum amount 35 of labor and attention in a manner to save time, the arrangement being preferably such that the operator can release either machine while standing at the other.

Further objects of the invention are in 40 part obvious and in part will appear more in detail hereinafter.

The invention comprises the construction and arrangement of parts hereinafter described and claimed.

45 In the drawings, Figure 1 represents a plan view, illustrating the invention applied to two machines located side by side; Fig. 2 is a side elevation from the right in Fig. 1, and shows one form of pressing machine to 50 which the invention may be applied; Fig. 3 is a front view of the treadle mechanism, illustrating a latch; and Fig. 4 is a plan view, illustrating another embodiment of the invention.

The invention may be applied to any form

of pressing machine, such as an ordinary garment press, a press adapted for special work, such as the pressing of underwear, ladies' garments, shirt cuffs, neckbands, and yokes, or the like, or the universal pressing machine shown in Fig. 2, said machine being adapted for pressing a wide variety of articles. Briefly stated, said machine comprises a frame or body 1 supporting a stationary lower pressing member 2 and having an upright standard or column 3 on which is pivoted an arm or lever 4 carrying the movable upper pressing member 5, which is adapted, by movement of said lever, to be moved into coöperating pressing relation with the lower pressing member 2.

Any suitable means may be provided for operating said lever for moving the pressing members into coöperating relation, the particular means shown being of the form illustrated, described and claimed in a prior application of Charles L. Braley for pressing machine, filed August 15, 1916, Serial No. 114,794. As illustrated herein it comprises a treadle 6 pivoted in the frame and carrying a roller 7 traveling on a cam face 8 of an intermediate lever 9 which supports a roller 10 traveling on a cam face 11 of a depending arm 12 attached to the arm or lever 4. When said treadle is depressed by applying the foot to the foot plate 13 thereon, the two rollers travel over their cam faces and depress the lever 4 so as to bring the two pressing members into coöperating relation.

As is customary in such machines, means is provided for holding or locking the upper pressing member in pressing relation with the lower pressing member. Said means, in the machine shown, comprises a latch 14 pivotally mounted at one side of the treadle 6 and having a depending hook member 15 adapted to engage a stationary hook 16 on the main frame when the treadle is depressed. To release the press or, in other words, to allow the upper pressing member to move away from the lower pressing member, said latch is provided with a projection 17 which may be engaged by a swinging release arm 18 to release the hook 15 from the stationary hook 16 whereupon the retracting spring 19 oscillates the arm 4 to the position shown in Fig. 2.

The release arm 18 is mounted upon a shaft 20 carried in brackets 21 on the frame base, and said arm 18 is usually provided

with a counterweight 22 which normally holds it out of engagement with the latch 14. It may be swung into engagement therewith, for releasing the press, by pressing 5 down on the foot plate 23^a of a short treadle arm 23 attached to the shaft 20.

Fig. 1 illustrates the operating levers of two pressing machines located side by side, each of said machines being of the form 10 shown in Figs. 2 and 3. The shaft 20 of one machine, marked A, extends laterally therefrom through a bearing 24, supported on the floor, its outer end being detachably coupled or connected in any suitable manner to the 15 shaft 20 of the other machine. As shown it extends into a coupling sleeve 25 pinned or otherwise attached to the end of the shaft 20 of the second machine B, said sleeve being provided with a clamping or set screw 26 20 for securing it non-rotatably to the shaft 20 of machine A. The treadle arms 6 and 23 are so formed that their foot plates lie closely adjacent to each other, as shown in Fig. 1.

The mechanism described operates as follows:—

The operator places a garment in machine A, and presses down upon the actuating treadle 6, so as to apply the pressure of the pressing members to said garment. The two 30 pressing members of machine A are held locked in pressing engagement by the lock or latch of machine A, shown in Fig. 3. The operator then steps over to machine B, which is opened or released, and places an article 35 or garment to be pressed upon the lower pressing member thereof. When said garment is properly arranged, sufficient time has elapsed to complete the pressing of the garment or article on machine A. The operator, therefore, applies her foot to the two 40 treadles 6 and 23 of machine B with the heel of the foot on pressure treadle 6, and the toe on the release treadle 23. Depression of the treadle 6 applies the pressure to machine B, while depression of treadle 23 oscillates the 45 two coupled shafts 20 and releases machine A. When both levers have been depressed and machine A is released, the operator turns her foot to one side or the other so as 50 to disengage it from the treadle 23, but holding it upon treadle 6. This allows the release arms 18 of the two machines to drop and enables the latching or locking mechanism of machine B to operate and lock the 55 pressing members thereof in pressing engagement with each other. The operator then steps over to machine A, removes the garment or article therefrom and places a new garment in position therein. She then 60 applies her foot to the treadles of machine A in the same manner as at machine B, thereby releasing machine B and producing pressing relation between the pressing members of machine A.

65 This arrangement enables a single opera-

tor to manipulate two machines with a single foot stroke, and with a minimum of travel and effort. It saves time and enables the operator to complete a greater amount of work than when the two machines are not 70 coupled to each other.

The two machines may also be located at any desired angle to each other. Fig. 4 illustrates a modification in which the two pressing machines marked A' and B', are located 75 at angles of 90° to each other. In this case, the shafts 20 of said machines are not only connected by the coupling sleeve 25, but also by some suitable means which allows the shafts 20 of the two machines to lie at an 80 angle to each other. This may, for example, be a universal or knuckle joint or two intermeshing bevel gears, as shown at 27. These machines are operated in the same manner as those before described. 85

With both arrangements described, two machines may be readily freed from coupling engagement with each other by unscrewing the clamping screw 26, thereby allowing the shafts 20 of the two machines to 90 rotate independently.

What I claim is:—

1. Apparatus of the class described, comprising a plurality of pressing machines, each embodying relatively movable pressing members and a plurality of controlling treadles therefor, and operating connections between treadles on different machines whereby operation of a treadle of one machine produces a controlling effect upon 100 another machine.

2. Apparatus of the character described, comprising a plurality of pressing machines, each embodying relatively movable pressing members, means for moving the pressing members of each machine into pressing relation, means for releasing each machine including operative connections between said machines whereby one machine can be released by operation of the said release means 110 for the release of another machine.

3. Apparatus of the character described, comprising a plurality of pressing machines, each embodying relatively movable pressing members, means for moving the pressing members of each machine into pressing relation, releasing means for each machine, operative connections between the releasing means of said machines to enable one machine to be released by operation of the release means of another machine. 115

4. Apparatus of the character described, comprising a plurality of pressing machines, each embodying relatively movable pressing members, operator-operated means for moving the pressing members of each machine into pressing relation and means for releasing the same, a part of said releasing means being located in close proximity to a part 125 of said first named means so as to be capable 130

of temporary operation as part of the same operating action applied to said first named means, and operative connections between said machines whereby one machine can be 5 released by operation of the said release means of another machine.

5. Apparatus of the character described, comprising a plurality of pressing machines, each embodying an operating treadle and a 10 release treadle, the two treadles of each machine having foot plates located adjacent to each other whereby both treadles may be depressed simultaneously, and operating connections between the release treadles of the 15 said machines.

6. Apparatus of the character described, comprising a plurality of pressing machines, each embodying coöperating pressing members, a treadle on each machine for producing 20 pressing relation between its pressing members, latching means on each machine for maintaining said relation, means on each machine for releasing the latching means thereof, and means whereby operation of the 25 releasing means of one machine releases the latching means of another machine.

7. Apparatus of the character described, comprising two pressing machines, each embodying coöperating pressing members, a 30 treadle on each machine for producing pressing relation between its pressing members, latching means for maintaining said relation, means on each machine for releasing the latching means thereof, and connections be- 35 tween the two machines whereby either machine may be released by an operator at the other.

8. Apparatus of the character described, comprising a plurality of pressing machines, 40 each embodying relatively movable pressing

members, means for closing said members, means for producing relative movement of said members to release them from pressing relation, and operating means at each machine operatively connected to another machine for causing actuation of the releasing means at said other machine independently 45 of the closing operation.

9. Apparatus of the character described, comprising a plurality of pressing machines, 50 each embodying relatively movable pressing members, means for positively latching the pressing members of each machine in pressing relation, and operating means at each machine operatively connected to another 55 machine for releasing the latching means of said other machine.

10. Apparatus of the character described, comprising two pressing machines, each embodying relatively movable pressing members, means for latching the pressing members of each machine in pressing relation, a pressure treadle and a release treadle at each machine, and means whereby actuation of the release treadle of one machine releases 65 the latching means of the other machine.

11. In apparatus of the class described, the combination with a plurality of pressing machines, each embodying relatively movable pressing members, and an operating 70 member therefor, of a mechanically actuated locking member for each operating member, and means at each machine for controlling all of said locking members.

In testimony whereof I affix my signature. 75

CHARLES L. BRALEY.
